[57] **CLAIM**

The ornamental design for book cover, as shown and described.

DESCRIPTION

FIG. 1 is a perspective view of the interior of a book-cover showing our new design in a fully opened position;

FIG. 2 is a perspective view of the exterior thereof; and, FIG. 3 is a perspective view thereof in a fully closed position, in use with a book shown in broken lines for illustrative purposes only, forming no part of the claimed design.

FIG. 1

FIG. 2

FIG. 3
